J. F. MAYER.
VEHICLE JACK.
FILED MAY 28, 1920.

UNITED STATES PATENT OFFICE.

JOSEPH F. MAYER, OF ST. LOUIS, MISSOURI.

VEHICLE JACK.

Application filed May 28, 1920. Serial No. 384,885.

To all whom it may concern:

Be it known that I, JOSEPH F. MAYER, a citizen of the United States, residing at St. Louis, Missouri, have invented a certain new and useful Improvement in Vehicle Jacks, of which the following is a full, clear, and exact description, such as will enable others skilled in the art to which it appertains to make and use the same.

10 This invention relates to vehicle jacks, and has for its main object to provide an efficient jack of simple design and inexpensive construction in which the operating mechanism consists of a worm arranged in 15 engagement with a spur gear that is provided with a screw-threaded opening through which the screw of the jack passes.

By using a spur gear instead of a worm gear to co-operate with the worm on the operating shaft, I materially reduce the cost of manufacturing the jack and I am able to arrange the operating shaft in an inclined position instead of a horizontal position, thereby producing a jack that is particularly 25 adapted for use in connection with automobiles, due to the fact that when the jack is arranged under one of the axles of an automobile the operating shaft inclines upwardly in such a position that it can be operated 30 easily by the user. The operating worm and the co-operating spur gear are journaled in a standard provided with a vertically-disposed bore in which the screw is arranged, and the wall of said bore is equipped with a 35 vertically-disposed slot that receives a laterally-projecting pin on the screw which prevents the screw from turning when the spur gear rotates, said slot being closed at both ends so as to eliminate the possibility of the 40 screw being raised high enough to carry it out of the standard.

Figure 1 of the drawings is a perspective view of a vehicle jack constructed in accordance with my invention.

45 Figure 2 is a vertical sectional view, taken through the upper portion of the standard of the jack, showing the spur gear in elevation.

Figure 3 is a horizontal sectional view, 50 taken through the housing in which the spur gear and operating worm are journaled.

Figure 4 is a side elevational view of the upper portion of the jack; and

Figure 5 is a perspective view of a pressed metal spur gear that can be used in place of the toothed gear shown in Figure 1.

Referring to the drawings which illustrate the preferred form of my invention, A designates the standard of the jack which 60 may consist either of a casting or a pressed metal standard, said standard comprising a vertically-disposed portion provided at its lower end with a base 1 and at its upper end with a housing 2 for receiving a horizontally-disposed spur gear B and an operating worm C; said housing being provided at one side with an opening through which the spur gear can be introduced into the housing. The screw D of the jack is arranged 65 vertically in a bore in the central portion of the standard A and projects upwardly through an internally screw-threaded hole in the spur gear B. Said screw is prevented from rotating relatively to the standard by 70 means of a laterally-projecting pin 3 on said screw that slides in a vertically-disposed slot 4 in the standard A, said slot being closed at its upper and lower ends so as to prevent the screw from being screwed upwardly out of the standard A.

The operating worm C is arranged at one side of the spur gear B in an inclined position, as shown in Figure 4, said worm being connected to an operating shaft C' directly 85 opposite the opening in the housing 2 through which the gear B is inserted. Said housing is provided with a laterally-projecting, continuous flange or box-like portion that encases the operating worm C and also 90 supports the operating shaft C', two of the opposed walls of said box-like portion being provided with integral bearings 5 and 6 in which the operating shaft is journaled. A

jointed or collapsible handle E is preferably 95 employed for turning the operating shaft C', said handle having a tubular portion that is adapted to be slipped over the end of the operating shaft so as to arrange a cross pin 7 on said shaft in a slot 7^a in said 100 handle, as shown in Figure 1. A friction reducing bearing, such, for example, as a ball bearing 8, is preferably arranged between the underside of the spur gear B and the bottom of the housing 2 in which said 105 gear is arranged so as to insure said gear turning easily. The spur gear of the jack can either consist of a cast gear or solid

2
gear provided with straight teeth, as shown in Figure 2, or the spur gear of the jack may be formed by a pressed metal member B', preferably substantially cup-shaped and provided in its annular portion with openings 9, as shown in Figure 5 for receiving the spiral rib on the operating worm.

A jack of the above construction can be manufactured at a low cost, owing to the fact that a spur gear instead of a worm gear is used in conjunction with the operating worm to raise and lower the screw D of the jack which gear is positioned in a housing that is open at one side so as to enable the gear to be slipped into the housing sidewise. Another desirable feature of such a jack is that the operating shaft can be arranged in an upwardly-inclined position, thereby enabling the jack to be positioned easily under the axle of an automobile and operated without requiring the user to stoop down or assume an awkward position. And other desirable features of the jack are the permanent connection between the screw and the standard which eliminates the possibility of the screw becoming detached from the standard and the integral,

box-like portion on the housing 2 that encases the work C.

Having thus described my invention, what I claim as new and desire to secure by Letters Patent, is:

A jack, comprising a standard provided at its upper end with a housing having an opening at one side, a horizontally-disposed spur gear in said housing of small enough diameter to permit it to be introduced sidewise through the opening at one side of the housing, a vertically-disposed screw in said standard that projects upwardly through an internally screw-threaded hole in said gear, a vertical slot in said standard closed at its upper and lower ends, a pin on said screw that projects outwardly through said slot, a laterally-projecting, box-like portion on said housing arranged opposite the opening in the housing through which said gear is inserted, an inclined operating shaft journaled in bearings on opposed walls of said box-like portion, and a worm on said operating shaft arranged in the box-like portion of the housing and meshing with the teeth of said spur gear.

JOSEPH F. MAYER.
